US0D1038421S

(12) **United States Design Patent** (10) Patent No.: **US D1,038,421 S**
(45) Date of Patent: ** Aug. 6, 2024

(54) **PERCUSSIVE MASSAGE DEVICE**

- (71) Applicant: **Therabody, Inc.**, Los Angeles, CA (US)
- (72) Inventors: **Jason Wersland**, Los Angeles, CA (US); **Benjamin Nazarian**, Beverly Hills, CA (US); **Jaime Sanchez Solana**, Los Angeles, CA (US); **Eduardo Merino**, Los Angeles, CA (US); **Trent Hernandez**, Los Angeles, CA (US)
- (73) Assignee: **Therabody, Inc.**, Los Angeles, CA (US)
- (**) Term: **15 Years**
- (21) Appl. No.: **29/870,541**
- (22) Filed: **Jan. 30, 2023**

Related U.S. Application Data

- (60) Continuation of application No. 29/828,340, filed on Feb. 25, 2022, now Pat. No. Des. 977,134, which is a continuation of application No. 29/728,608, filed on Mar. 19, 2020, now Pat. No. Des. 949,390, which is a division of application No. 29/708,804, filed on Oct. 9, 2019, now Pat. No. Des. 879,985, which is a continuation-in-part of application No. 29/674,838, filed on Dec. 26, 2018, now Pat. No. Des. 880,715.
- (51) **LOC (14) Cl.** **24-01**

CLAIM

The ornamental design for a percussive massage device, as shown and described.

DESCRIPTION

FIG. 1 is a top perspective view of a percussive massage device showing the claimed design;

FIG. 2 is a right side elevational view, the left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a bottom perspective view thereof.

The broken lines in the figures show portions of the percussive massage device that form no part of the claimed design.

1 Claim, 5 Drawing Sheets
